[57] CLAIM

The ornamental design for a faucet body, as shown and described.

DESCRIPTION

FIG. 1 is a left perspective view of a faucet body showing our new design;

FIG. 2 is a left side elevational view thereof, the right side being a mirror image of the left side;

FIG. 3 is a top plan view thereof;

FIG. 4 is a front elevational view thereof; and

FIG. 5 is a rear elevational view thereof.

The broken line representation of a handle in FIG. 1 and an aerator in FIGS. 1 and 2 is for the purposes of illustration only and forms no part of the claimed design.
